GARBAGE DISPOSAL DEVICE

George B. Long, Dayton, Ohio, assignor to General Motors Corporation, Detroit, Mich., a corporation of Delaware

Application September 28, 1954, Serial No. 458,731

4 Claims. (Cl. 241—46)

This application is a continuation-in-part of my co-pending applications S. N. 329,970 filed January 7, 1953, and S. N. 422,644 filed April 12, 1954.

This invention relates to a domestic appliance and more particularly to garbage disposal units.

One of the more serious difficulties with garbage disposal units is the possibility of jamming the impeller. Another difficulty is the fact that the garbage disposer must be flushed during the grinding operation to avoid clogging and jamming.

It is an object of my invention to provide a simple inexpensive garbage disposer which will not jam or clog and which will not grind the material unless it is being flushed with liquid.

It is another object of my invention to provide a garbage disposer with an impeller arrangement which will rotate freely when no liquid is being flushed through the disposer and which will not cut or grind the garbage unless liquid is present and the impeller is operating above a predetermined speed.

These and other objects are substantially attained in the form shown by providing an impeller having one or more vanes which are lifted by reaction with liquid when they are revolved within the cutting chamber with liquid flowing through and out of the cutting chamber.

Further objects and advantages of the present invention will be apparent from the following description, reference being had to the accompanying drawings wherein a preferred form of the invention is clearly shown.

In the drawings:

Figure 1 is a diagrammatic view of a faucet, sink, garbage disposer and drain;

Figure 2 is a fragmentary vertical sectional view through the garbage disposer disclosed in Figure 1;

Figure 3 is a sectional view taken substantially along the lines 3—3 of Figure 2;

Figure 4 is a sectional view similar to Figure 2 but with the impeller turned 90° and shown in elevation; and

Figure 5 is a sectional view similar to Figure 4 but showing the vane in elevated position.

Referring now to the drawings and more particularly to Figure 1 there is shown a sink 20 provided with a faucet 22 and an outlet 24 to which is connected the garbage disposal unit 26. This garbage disposal unit 26 is adapted to discharge through a trapped drain connection 28.

The garbage disposer 26 includes upper walls 30 in the shape of a truncated hollow cone enclosing a cutting chamber 32. The bottom portion of the cutting chamber 32 is provided with a shredder ring 34 preferably of suitably hardened stainless steel or cast stainless alloy. The shredder ring 34 is provided with four sharp edged groups of projections 36 composed of wide trapezoidal projections arranged one upon the other in a manner similar to lap siding excepting that they are arranged in the reverse direction. These groups 36 are staggered

2

vertically to prevent any grooving action. They have ground surfaces with sharp cutting edges which protrude inwardly from the inner wall surfaces of the shredder ring 34.

Concentrically located within the bottom portion of the shredder ring 34 is the impeller 38 threaded onto and fastened to the top of the drive shaft 40 of an electric motor 42. The cutting chamber 32 is separated from the motor 42 by a transverse wall 44 containing the ball bearing 46 and a running shaft seal 48 for the drive shaft 40.

Upon opposite sides of the impeller 38 there are provided the pivoted appearing and disappearing identical vanes 50 and 52. The vane 50 is pivoted upon the screw 54 to the impeller 38 while the vane 52 is pivoted upon the screw 56 to the impeller 38. As shown in Figure 4 the vanes 50 and 52 are generally semicircular and on their right half are provided with three radially extending projections 58, 60 and 62. The impeller 38 is provided with a stop surface 64 against which rests the portion of the vane 50 nearest the projection 52 when the vane is held solely by gravity as shown in Figure 4. This position is due to the fact that the vane 50 is substantially semicircular and naturally will under the force of gravity alone tend to assume the position wherein the mid-portion of the vane hangs downwardly. In this position, the projection 68 disappears beneath the top of the impeller 38 so that it cannot engage any garbage within the chamber 32. The impeller 38 then revolves freely without any cutting action. The projections 58, 60 and 62 are adapted to extend into a groove 66 in the transverse wall 44 extending between the motor 42 and the cutting chamber 32.

The disposer 26 is designed to be operated with the faucet 22 turned on. This causes water to flow from the faucet 22 into the sink 20 and downwardly through the opening 24 into the cutting chamber 32. This flow of water carries the ground material down to the impeller 38 and out through the space between the impeller 38 and the adjacent portion of the shredder ring 34. This water and ground material fills the groove 66. The rotation of the impeller 38 by the motor 42 when the water or other liquid is flowing through the disposer causes the groove 66 to be kept substantially full of liquid. When the motor 42 rotates the shaft 40 and the impeller 38, the projections 58, 60 and 62 will be dragged in a counterclockwise direction through the groove 66 and will react with the liquid in the groove 66. This will cause the projecting portion 68 of the vane 50 and a similar portion of the vane 52 to be carried upwardly by the reaction to the appearing or projected position shown in Figure 5. In this position, the portion 68 projects upwardly through a recess in the edge portion of the impeller 38 and will engage any garbage material in the bottom of the grinding chamber 32 and carry this garbage material around into contact with the cutting edges on the shredder ring 34 to grind the material sufficiently fine to have it be carried to the drain by the water which is being flushed through the disposer. The groove 66 discharges into a laterally extending outlet 70 which connects to the trap connection extending to the drain.

By this arrangement no cutting can take place until there is a continuous supply of flushing liquid or other material in the groove 66 since liquid is required to lift the vanes 50 and 52. This automatically assures that there will be no cutting action in the event that the user fails to open the faucet 22 to supply the required flushing liquid for carrying away the ground material through and out of the disposer 30. The vanes 50 and 52 disappear as shown in Figure 4 before the impeller 38 stops at the end of an operating cycle and do not reappear until the speed of rotation is sufficient to cause

a reaction with the contents of the groove 66 so that the vanes 50 and 52 are projected upwardly as shown in Figure 5.

While the form of embodiment of the invention as herein disclosed constitutes a preferred form, it is to be understood that other forms might be adsorbed, as may come within the scope of the claims which follow.

What is claimed is as follows:

1. Comminuting apparatus including metal walls provided with cutting edges enclosing a cutting chamber, an impeller located in the bottom portion of said cutting chamber, a transverse wall forming the bottom of said cutting chamber, said transverse wall being provided with an annular groove concentric with said impeller and an outlet from said groove, a motor connected to said impeller for rotating the impeller, said impeller being provided with a movable appearing and disappearing vane, said vane being provided with a lifting projection extending into said groove for lifting the vane when the impeller rotates and the projection impinges upon liquid in the groove.

2. Comminuting apparatus including metal walls provided with cutting edges enclosing a cutting chamber, an impeller located in the bottom portion of said cutting chamber, a transverse wall forming the bottom of said cutting chamber, said transverse wall being provided with an annular groove concentric with said impeller and an outlet from said groove, a motor connected to said impeller for rotating the impeller, said impeller being provided with a movable appearing and disappearing vane having an appearing position in which it projects above the impeller and a disappearing position in which it disappears below the top surface of the impeller and projects into said groove, said vane being provided with a lifting portion projecting into said groove.

3. Comminuting apparatus including metal walls provided with cutting edges enclosing a cutting chamber, an impeller located in the bottom portion of said cutting chamber, a transverse wall forming the bottom of said cutting chamber, said transverse wall being provided with an annular groove concentric with said impeller and an outlet from said groove, a motor connected to said impeller for rotating the impeller, said impeller being provided with a movable appearing and disappearing vane, being pivotally connected to said impeller and having a lifting projection extending into the groove, means for supplying liquid to said cutting chamber for carrying comminuted material out of the cutting chamber and for filling said groove to lift said vane when said motor operates.

4. Comminuting apparatus including metal walls provided with cutting edges enclosing a cutting chamber, an impeller located in the bottom portion of said cutting chamber, a transverse wall forming the bottom of said cutting chamber, said transverse wall being provided with an annular groove concentric with said impeller and an outlet from said groove, a motor connected to said impeller for rotating the impeller, said impeller being provided with a movable appearing and disappearing vane, said vane being pivotally connected to said impeller and having a plurality of spaced radially extending lifting projections extending into the groove, means for supplying liquid to said cutting chamber for carrying comminuted material out of the cutting chamber and for filling said groove to lift said vane when said motor operates.
